(57) **CLAIM**

The ornamental design for a cart, as shown and described.

DESCRIPTION

FIG. 1 is a top perspective view of a cart showing my new design;

FIG. 2 is a top plan view thereof;

FIG. 3 is a front elevational view thereof;

FIG. 4 is a left side elevational view thereof;

FIG. 5 is a right side elevational view thereof;

FIG. 6 is a rear elevational view thereof; and,

FIG. 7 is a top perspective view thereof, showing an alternate position of the drawers.

In the drawings, the broken lines representing elements such as handles, hooks, plate, plate holder, support rods, and garbage container are for illustrative purposes only and form no part of the claimed design.

1 Claim, 6 Drawing Sheets
